CLAIM

The ornamental design for an impact biopsy device, as shown and described.

DESCRIPTION

FIG. 1 is a perspective view of an impact biopsy device. FIG. 2 is a second perspective view of the impact biopsy device of FIG. 1.

FIG. 3 is a front view of the impact biopsy device of FIG. 1. FIG. 4 is a right side view of the impact biopsy device of FIG. 1. A left side view of the impact biopsy device of FIG. 1 would be a mirror image of the right side view shown in FIG. 5.

FIG. 5 is rear view of the impact biopsy device of FIG. 1. FIG. 6 is an enlarged top view of the impact biopsy device of FIG. 1; and,

FIG. 7 is an enlarged bottom view of the impact biopsy device of FIG. 1.

1 Claim, 4 Drawing Sheets
